NOISE REDUCTION SYSTEM

John D. Reid, Philadelphia, Pa., assignor to Radio Corporation of America, a corporation of Delaware

Application June 27, 1939, Serial No. 281,333

9 Claims. (Cl. 250—20)

This invention relates to noise reduction systems such as are utilized to eliminate the undesired noise produced in radio receiving apparatus by electrical impulses other than those of the desired signal, and has for its principal object the provision of an improved system and method of operation whereby such noise is eliminated.

As pointed out in a copending Landon application, Serial No. 210,323, filed May 27, 1938, and 10 assigned to the same assignee as the present application, much of the noise encountered in radio reception is due to undesired electrical impulses which come into the receiver over the power supply line and produce a noise voltage between the 15 receiver chassis and ground. While this noise voltage may be reduced by the use of a short ground lead, the use of a sufficiently short lead is usually impracticable. In accordance with the aforesaid Landon application, this difficulty is 20 avoided by the provision of an improved noise reduction system including long and short antennae which are interconnected through the primary winding of a transformer provided with a tuned secondary winding through which signal 25 impulses are applied to the input circuit of the first stage of the amplifier. These two antennae are spaced from one another by a distance of a few inches to a few feet, and a variable balancing condenser is connected between the long antenna and the chassis.

If there were no capacity coupling between the primary winding and the secondary winding or chassis of this Landon noise reduction system, the balancing condenser would not be required. 30 Due to the existence of such capacity, however, the noise voltage on the chassis induces noise voltage in both the antennae. The function of the balancing condenser is to neutralize the noise voltage otherwise produced in the secondary winding 35 and in the amplifier input circuit. If the noise voltages induced in the two antennae were equal in phase and amplitude, no noise current would follow in the primary winding. The long antenna, however, is generally of lower impedance 40 and has less noise voltage induced in it until the condenser is adjusted to produce a balance. If capacity exists between the primary winding and the high potential side of the secondary winding, a change in the balance point is desirable for the 45 reason that neutralization of this capacity minimizes the effect of frequency change on the balance point.

The present invention is similar to that of the aforesaid copending application in that it involves the use of a counterpoise and balancing

condenser, but is distinguished therefrom in that 5 (1) it is adapted to multi-range reception and (2) it avoids the necessity of any switching on the primary side of the input transformer. In this improved system, noise reduction is effected at high frequencies by means of a balanced input system and a twisted pair antenna lead-in, and at low frequencies by means of a counterpoise and balancing condenser.

The invention will be better understood from 10 the following description considered in connection with the accompanying drawing, and its scope is indicated by the appended claims.

Referring to the drawing:

Figure 1 is a wiring diagram of the improved 15 noise reduction as applied to a two-frequency band receiver.

Figure 2 is a similar diagram of a modified two-frequency band receiver wherein the antenna lead-in and counterpoise are in the form 20 of a concentric line, and

Figure 3 illustrates the application of the invention to a receiver of the three-frequency band type.

The system of Fig. 1 includes a dipole antenna 10 which is connected through the twisted pair lead 11 to the primary winding 12 of a high frequency input transformer 13. The primary winding 12 is provided with an intermediate terminal 14 which is connected to one terminal of a balancing condenser 15 and is also connected through the primary winding 16 of a low frequency input transformer 17 to a counterpoise or relatively short antenna 18. The secondary winding 19 of the high frequency input transformer 13 is connected at one end to a coupling condenser 20 and at the other end, through the secondary winding 21 of the low frequency transformer 17, to the chassis which is indicated at 22. Connected to the chassis 22 are also one terminal 30 of the balancing condenser and the low voltage side of a transformer secondary tuning capacitor 23. In order to facilitate high frequency reception, a switch 24 is provided for short-circuiting the low frequency secondary winding 21. 35

Through the coupling capacitor 20, signal impulses are applied to the input circuit of a radio frequency amplifier 25. The output circuit of the amplifier 25 is coupled to the input circuit of an amplifier 26 through a coupling capacitor and either a high frequency band input transformer 27 or a low frequency band transformer 28, depending on the position of a band selecting switch 29. A switch 30 is provided for short-circuiting the secondary of the transformer 28. 50 55

when high frequency band signals are to be received. The arrangement and function of other illustrated features of the system will be apparent without detailed explanation. The noise reduction features with which this invention is particularly concerned are, of course, found in the antenna input network preceding the amplifier 25.

As previously indicated, the switch 24 is closed 10 during high frequency band reception, and noise reduction is effected by means of the dipole, twisted pair lead-in and balanced primary input connection. During low frequency band reception, the switch 24 is open, the dipole, the twisted 15 pair lead-in and the low frequency primary 12 function to pick up the signal, and the noise impulses are balanced out by adjusting the capacitor to such a value that the noise voltages at opposite ends of the low frequency primary winding 20 16 are equal in value and of opposite phase. Under these conditions, no noise current flows in this primary winding and no noise voltage is induced in the secondary winding 21.

The modification of Fig. 2 is similar to that of 25 Fig. 1, with the exception that the twisted pair lead-in is replaced by a concentric line 31—32. It is important to keep the capacity low and symmetrical from either side of the line to the grid end of the secondary winding 19, and to 30 keep the capacity of the low frequency transformer low so that the balance point will remain substantially the same over the low frequency band. The balancing capacitor 15 may be pre-adjusted or used for exact balancing which varies as the frequency of the tuning is varied. As disclosed by the aforesaid Landon application, a resistor in series with the capacitor 15 is often effective in securing a better balance, and a ground connection including a capacitor may be 40 utilized instead of the counterpoise.

Fig. 3 illustrates a three-band receiving system which functions to receive a medium frequency band intermediate the bands received by the systems of Figs 1 and 2. To this end, there is 45 provided an additional input transformer 33 and a frequency band selection switch 34 which is operated to its upper closed position for selecting the frequency band passed by the transformer 13, is operated to its central closed position for selecting the frequency band passed by the transformer 17, and is operated to its lower closed position for selecting the frequency band passed by the transformer 33. It will be noted that the 50 primary winding of the transformer 33 is shunted by a capacitor 35 which is of such value as to make the resonance of the primary of the transformer 17, together with the antenna, fall at the lower end or just outside the tuning range of the secondary winding of the transformer 17.

This system, like those previously described, has the advantage that it avoids switching in the primary circuits, thus enabling the primary to ground and the primary to secondary capacitances to be kept low. If an antenna of dimensions suitable for the long wave band is used, it is resonant in the medium band and a balance cannot be obtained on the medium band, although there is an improvement in noise reduction over the conventional receiver grounded to the chassis. In most cases, further improvement in noise reduction can be secured by the use of a variable resistor connected in series or parallel with the balancing resistor, as pointed out in the 70 aforesaid Landon application.

I claim as my invention:

1. In a radio apparatus including a chassis which tends to be maintained at a noise voltage with respect to ground, the combination of high and low frequency band input transformers each provided with primary and secondary windings, antenna means connected to the opposite end terminals of said high frequency band primary winding, and counterpoise means connected through said low frequency band primary winding to an intermediate terminal of said high frequency band primary winding. 5

2. In a radio apparatus including a chassis which tends to be maintained at a noise voltage with respect to ground, the combination of high and low frequency band input transformers each provided with primary and secondary windings, antenna means connected to the opposite end terminals of said high frequency band primary winding, counterpoise means connected through 10 said low frequency band primary winding to an intermediate terminal of said high frequency band primary winding, and capacitor means connected between said chassis and said intermediate terminal for excluding said noise voltage from 15 said low frequency band primary winding. 20

3. In a radio apparatus including a chassis which tends to be maintained at a noise voltage with respect to ground, the combination of a plurality of different frequency band transformers each provided with primary and secondary windings, antenna means connected to the opposite end terminals of one of said primary windings, counterpoise means connected to an intermediate terminal of said primary winding 35 through another of said primary windings, and a balancing capacitor connected between said chassis and said intermediate terminal. 30

4. In a radio apparatus including a chassis which tends to be maintained at a noise voltage 40 with respect to ground, the combination of a plurality of different frequency band transformers each provided with primary and secondary windings, antenna means connected to the opposite end terminals of one of said primary windings, counterpoise means connected to an intermediate terminal of said primary winding 45 through another of said primary windings, a balancing capacitor connected between said chassis and said intermediate terminal, and means for connecting said secondary windings in an output network having its low voltage side connected to said chassis. 50

5. In a radio apparatus including a chassis which tends to be maintained at a noise voltage 55 with respect to ground, the combination of a plurality of different frequency band transformers each provided with primary and secondary windings, antenna means connected to the opposite end terminals of one of said primary windings, counterpoise means connected to an intermediate terminal of said primary winding through another of said primary windings, a balancing capacitor connected between said chassis and said intermediate terminal, means for connecting said secondary windings in an output network provided with a high voltage terminal and with a low voltage terminal connected to said chassis, and means for connecting the high voltage side of either of said secondary windings to said high voltage terminal. 60

6. In a radio apparatus including a chassis which tends to be maintained at a noise voltage with respect to ground, the combination of three different frequency band transformers each pro- 70

vided with primary and secondary windings, antenna means connected to the opposite end terminals of the highest frequency primary windings, counterpoise means connected to an intermediate terminal of said primary winding through the lower frequency primaries of said primary windings, a balancing capacitor connected between said chassis and said intermediate terminal, means for connecting said secondary windings in an output network provided with a high voltage terminal and with a low voltage terminal connected to said chassis, and means for connecting the high voltage side of either of said secondary windings to said high voltage terminal.

7. In a radio apparatus including a chassis which tends to be maintained at a noise voltage with respect to ground, the combination of a plurality of different frequency band transformers each provided with primary and secondary windings, antenna means connected to the opposite end terminals of one of said primary windings, counterpoise means connected to an intermediate terminal of said primary winding through another of said primary windings, a balancing capacitor connected between said chassis and said intermediate terminal, a shunt condenser connected across the lowest frequency primary, means for connecting said secondary windings in an output network provided with a high voltage terminal and with a low voltage terminal connected to said chassis, and means for connecting the high voltage side of either of

said second windings to said high voltage terminal.

8. In a radio apparatus including a chassis which tends to be maintained at a noise voltage with respect to ground, the combination of high and low frequency band signal input transformers each provided with primary and secondary windings, said primary winding having two end terminals and an intermediate terminal, means providing a dipole antenna connection for the end terminals of said high frequency band primary winding, and means providing a second antenna connection serially through said low frequency band primary winding to said intermediate terminal of said high frequency band primary winding, and means providing a balancing capacity between said chassis and said intermediate terminal.

9. In a radio apparatus including a chassis which tends to be maintained at a noise voltage with respect to ground, the combination of high and low frequency band input transformers each provided with primary and secondary windings, said primary winding having two end terminals and an intermediate terminal, a transmission line, antenna means connected to the opposite end terminals of said high frequency band primary winding through said line, and counterpoise means comprising a conductor connected through said low frequency band primary winding to said intermediate terminal of said high frequency band primary winding and associated with said transmission line.
